UNITED STATES PATENT OFFICE.

JOHN ZELLWEGER, OF ST. LOUIS, MISSOURI.

AIR-PURIFYING MACHINE.

985,963.

Specification of Letters Patent. Patented Mar. 7, 1911.

Application filed May 31, 1910. Serial No. 564,256.

To all whom it may concern:

Be it known that I, JOHN ZELLWEGER, a citizen of the United States, residing at St. Louis, Missouri, have invented a certain new and useful Improvement in Air-Purifying Machines, of which the following is a full, clear, and exact description, such as will enable others skilled in the art to which it appertains to make and use the same.

10 This invention relates to air-purifying machines, and particularly to machines of that type which comprise a rotating filter ring through which the air passes, and means for supplying water to said filter ring so as to 15 wash and purify the air.

One object of my present invention is to provide a machine of the type referred to which is so designed that the wash water will circulate through the machine continuously while the machine is in operation and thus overcome the necessity of connecting the machine to a source of water supply.

Another object is to provide an air-purifying machine which is so designed that the wash water will be separated from the air and prevented from escaping from the machine with the purified air.

Another object is to provide a machine of the type referred to that discharges a greater quantity of air and which is more efficient than the air-purifying machines heretofore in use.

Another object is to provide a machine of the type referred to which is so designed that a body of wash water will be maintained at practically a constant level in the machine when the machine is in operation. And still another object is to provide an air-purifying machine of the type referred to that can be used successfully on railway cars and street cars.

Other objects and desirable features of my invention will be hereinafter pointed out.

My improved machine, briefly described, 45 consists of a rotating filter ring arranged in such a manner that air will be drawn into same and discharged from the exterior thereof, one or more devices arranged inside of the filter ring for introducing water 50 onto same, a water-collecting reservoir communicating with said devices so as to supply water thereto and arranged in such a manner that it receives the wash water which is discharged from the filter ring, a

tank or means for maintaining a body of 55 water adjacent the filter ring, and means for automatically conveying the water from said tank to said collecting reservoir. The machine is also provided with means for preventing the wash water which escapes from 60 the filter ring from leaving the machine with the filtered air, and in the preferred form of my invention means is provided for automatically supplying water to the tank which is arranged adjacent the filter ring when the 65 water in said tank drops below a certain level.

In the various embodiments of my invention herein shown the filter ring is arranged horizontally and on the inside of a ring-shaped collecting reservoir which is located adjacent the upper end of the filter ring or in a higher horizontal plane than that in which the filter ring lies. The air which is to be purified may enter either the top or the bottom of the filter ring and the tank which contains the water that is conveyed to the collecting reservoir is located adjacent the lower end of the filter ring. Various means can be used for conveying the water from 80 said tank to said reservoir, such, for example, as an approximately inverted cone-shaped member arranged to rotate with the filter ring and having its upper and lower edges terminating adjacent said collecting 85 reservoir and tank, respectively, or, if desired, the water-lifting means may consist of an approximately inverted cone-shaped member arranged adjacent the tank for delivering the water in said tank to a rotating 90 cylinder up which it travels to a trough provided with a riser pipe that discharges into the collecting reservoir.

Figure 1 of the drawings is a vertical sectional view illustrating the preferred form 95 of my invention, taken on approximately the line I—I of Fig. 2; Fig. 2 is a horizontal sectional view of the machine shown in Fig. 1, the upper quarter of this view being taken on approximately the line II—II of 100 Fig. 1, the righthand quarter being taken on approximately the line III—III of Fig. 1, the lower quarter being taken on approximately the line IV—IV of Fig. 1, and the lefthand quarter being taken on approximately the 105 line V—V of Fig. 1; Fig. 3 is a vertical sectional view of a slightly modified form of my invention; Fig. 4 is a vertical sectional

view of another modification; and Fig. 5 is a vertical sectional view of still another modification.

Referring to Fig. 1 which illustrates the preferred form of my invention, 1 designates the stationary casing of the machine which is preferably cylindrical-shaped and provided with a horizontally disposed bottom. A pedestal 2 that projects upwardly from the bottom of the casing carries a bearing 3 which supports a spider 4 connected to a vertically disposed shaft 5 which is rotatably mounted in said bearing and provided with a pulley 6 or other suitable means for imparting rotary movement thereto. The spider 4 supports the filter ring which in the embodiment of my invention herein shown consists of a cylinder 7 provided in its lower portion with perforations and having a number of layers of filtering material 8, preferably of wire cloth, arranged on the inner side of same adjacent said perforations. Vanes or blades 9 project radially from the cylinder 7, and an approximately inverted cone-shaped member 10 is arranged outside of the cylinder 7 and is securely connected to the vanes 9 so that it will rotate with the filter ring. This inverted cone-shaped member 10 extends from a point adjacent the lower end of the cylinder 7 to a point above the level of the filter ring, but it is spaced away from the cylinder 7 throughout its entire length so that water can travel upwardly over the inner surface of the member 10, as hereinafter described. The vanes 9 extend to the upper end of the cylinder 7 and support a cover 11 whose peripheral edge is deflected downwardly so as to form a flange 11^a, said cover being provided with an opening A through which the air is drawn into the filter ring when said ring is rotated. A partition 12 which preferably conforms to the shape of the inverted cone-shaped member 10, is arranged inside of the casing 1 so as to surround the member 10, and a horizontally disposed ring-shaped partition 13 is interposed between the partition 12 and the casing 1 to form an annular-shaped trough 14 which serves as a collecting ring or reservoir for the circulating water, the space under this collecting ring being utilized as a storage tank 15 for fresh water. The casing 1 is provided at its upper edge with an inwardly and upwardly inclined flange 16 which extends from a level below the top of the inverted cone-shaped member 10 on the filter ring to a level above said member so as to cover the trough or collecting ring 14 and thus deflect the water which is thrown from the upper edge of the member 10 downwardly into said trough.

A plurality of sprinkling pipes 17, which are arranged inside of the filter ring 8, are provided with holes 18 through which jets

of water escape onto the inner surface of the filter ring, and feed-pipes 19 are provided for establishing communication between these sprinkling pipes and the trough or water reservoir 14 so as to cause the water to circulate from said reservoir back to the devices which introduce the wash-water onto the filter ring. The feed-pipes 19 are provided with perforated drain plugs 20 which can be opened when it becomes necessary to flush out said pipes so as to discharge the sediment that collects therein.

The fresh water reservoir 15 is provided adjacent its upper end with a supply opening 21 and at its lower end with a discharge opening 22 through which the fresh water can escape into the tank 31 formed by the bottom of the casing and the partition 12, a valve 23 being provided for controlling the supply of fresh water from the reservoir 15 into the tank 31. I prefer to provide the machine with means for automatically opening and closing the valve 23 when the water in the tank 31 rises or falls above or below a certain level so as to maintain practically a constant level in said tank, and the means herein shown for accomplishing this consists of a valve-operating lever 24 provided with a pivotally mounted arm 26, as shown in Fig. 2, to which floats 25 are connected. The reference characters 27 and 28 designate drain openings in the bottoms of the fresh water reservoir 15 and the tank 31, respectively.

The spider 4, the cylinder 7, the filter ring 8, the vanes 9, and the inverted cone-shaped member 10 constitute the filter wheel of the machine, and when this filter wheel is rotated rapidly the air in the spaces of the filter ring and between the vanes 9 is carried along in a circular course and thus acquires centrifugal force. Under action of this force the air in that part of the spaces between the vanes which is above the inverted cone 10, is thrown out of the wheel and replaced by air from that part of the vane spaces which is below the top of the inverted cone-shaped member 10, this air in turn being replaced by air from the filter ring. More air follows into the filter ring by the atmospheric pressure from the center space of the wheel and the result is a continuous flow of air through the filter ring, perforated cylinder 7, vane spaces, and the annular pressure chamber 29 between the stationary deflector 16 of the casing and the downwardly inclined flange 11^a of the cover 11, said air being discharged all around the casing and in a downward direction. The rotary movement of the inverted cone-shaped member 10 causes the water in the tank 31 to be set in rotation due to frictional engagement, and this water acquires sufficient centrifugal force to cause it to rise on the inner face of the inverted

cone-shaped member 10 and to be thrown over the edge of said member tangentially and in the plane of rotation against the inside face of the deflector 16 which deflects 5 the water downwardly into the collecting trough or reservoir 14. The water passes from the trough 14 through the feed pipes 19 to the sprinkling pipes 17 and is discharged from said pipes in the form of a 10 fine spray or jets over the inner face of the rapidly rotating filter ring 8. When the water jets strike the wire cloth or material from which the filter ring is composed, they are scattered into water drops and mist 15 which are carried into the filter ring by the inflowing air, the water being thus spread in a thin film over the entire surface of the filtering material and being rotated in a circular course. The centrifugal force throws 20 the water outwardly through the spaces of the filter ring and through the perforated cylinder into the spaces between the vanes 9 and against the inner face of the inverted cone-shaped member 10 where it mingles 25 with the water which said member is raising out of the tank 31 and into the collecting ring or reservoir 14. The excess of water raised by the inverted cone-shaped member 10 into the collecting reservoir 14 over the 30 quantity that can be discharged by the sprinkling pipes 17, is allowed partly to flow over the upper edge of the partition 12 into the tank 31, and partly to flow out of the perforated drain plugs 20 from the feed pipes 35 19 into said tank 31.

During its passage through the wet filter ring the air current is rapidly divided, mingled and re-divided into as many small currents as there are meshes in the wire cloth 40 of the filter ring, and at the same time the air is made to impinge rapidly onto the water which passes over said wire cloth. This repeated forcible contact of the air with the water causes all dust particles floating in 45 the air to be projected onto the water film and there to be retained by adhesion. All impurities taken up by the water are continually washed out of the filter ring by the re-circulating wash water and accumulated 50 therein to a degree which makes it necessary to dilute it by a quantity of fresh water and to waste some of the water through a drain from the bottom of the tank 31 either continually or periodically, the drains 20 being 55 used to wash out the impurities which tend to settle in the feed pipes 19. Whenever water is drained out of the bottom of the tank 31 the floats 25 descend and thus cause the valve 23 to be opened so as to permit 60 fresh water to flow from the reservoir 15 through the opening 22 into said tank, and when the required level is attained said floats exert sufficient pressure on the lever 24 to hold the valve 23 seated. The same operation 65 is caused by the escape of some of the

wash water in the form of vapor with the air and the consequent lowering of the water level in the tank 31.

While I do not wish it to be understood that my invention is limited to any particular means for automatically opening and closing the valve which controls the supply of water to the tank 31, still I prefer to employ valve-controlling means of substantially the form herein shown on machines 70 that are used in cars and vehicles which are subjected to a more or less rolling motion for the pivotally mounted arm 26 on the lever 24 which connects the floats 25 to said lever permits the water in the tank 31 to 80 move to and fro without disturbing or affecting the valve 23.

A machine of the construction herein shown overcomes the necessity of using a constant supply of wash water, for the inverted cone-shaped member 10 automatically feeds the water from the tank 31 into the collecting trough or reservoir 14 from which the pipes 19 lead to the sprinkling pipes 17 on the inner side of the filter ring. The 85 machine is compact and is so designed that no water in the form of a spray or drops can escape from the machine, for the deflector 16 which is arranged over the collecting trough separates the water that is thrown 90 out of the filter ring with the air. The air after passing through the wet filter ring is discharged from the pressure chamber 29 thoroughly purified of all dust and about ninety per cent. saturated with moisture. 95 Furthermore, the air is also cooled or warmed according to its original temperature and the temperature of wash water that is used to purify the air. While I have herein stated that the air is discharged all 100 around the casing I do not wish it to be understood that my invention is limited to such a structure for, if desired, the air that is discharged from the filter ring could be collected and delivered to suitable deliverying ducts or conduits. 110

In Fig. 3 I have illustrated a machine which is practically the same as the one shown in Figs. 1 and 2 except that it is not provided with a fresh water reservoir 15, the partition 12^a being of substantially cylindrical shape and spaced a slight distance away from the cylindrical wall of the casing 1 so as to form a comparatively deep trough 115 or collecting reservoir 14^a with which the feed pipes 19 communicate. 120

As previously stated, various other means than the inverted cone-shaped member 10 can be employed for feeding the water from the tank 31 to the collecting reservoir 14, and in Fig. 4 I have shown a machine that is provided with a slightly different form of means for raising the water from the tank into the collecting reservoir. In the form of my invention shown in Fig. 4 a motor 6^a on the 125 130

shaft 5 to which the supporting spider 4 is connected, rests on the bearing 2^a, and the casing 1^a is made substantially ring-shaped so as to provide an opening for said bearing 5 and pulley. An inverted cone-shaped member 10^a is arranged adjacent the lower end of the filter ring so that it will project into the water in the tank 31, and a cylinder 10^b is arranged above said inverted cone-shaped 10 member. An accumulator 10^c is arranged at the upper end of the cylinder 10^b and a riser pipe 10^d, which projects upwardly from said accumulator, is utilized for conducting the water from said accumulator into the 15 ring-shaped trough or collecting reservoir 14^c. When the filter wheel is rotated the water in the tank 31 travels upwardly over the inverted cone-shaped member 10^a and flows through the openings 30 in the plate 20 which supports said member against the cylinder 10^b. The water keeps accumulating and rising on said cylinder until it overflows into the accumulator 10^c which preferably consists of a ring-shaped trough, and 25 when said trough is filled the water therein rises into the pipe 10^d from which it subsequently flows into the collecting ring 14^c from which it is conveyed by the pipes 19 back to the sprinkling pipes 17. The vanes 30 9^a in this form of my invention are of slightly different construction from the form shown in Fig. 1 and only occupy the upper part of the space between the cylinder 7 of 35 the filter wheel and the means that lifts the water from the tank 31 into the collecting trough.

In Fig. 5 I have illustrated a machine which differs from the machines previously described in that the air is taken in through 40 the lower end of the filter ring, and, further, that the tank which holds the water that is fed to the collecting reservoir rotates with the filter ring instead of being stationary, said tank being designated by the reference 45 character 31^a and having a side wall 10^g of approximately inverted cone-shape. The rotary movement of the filter wheel causes the water in the tank 31^a to rise on the inverted cone-shaped wall 10^g thereof, and when the 50 water reaches the upper edge of said wall it is discharged outwardly into the collecting ring or reservoir 14^d from which it flows back to the sprinkling pipes 17 through the feed pipes 19, some of the water escaping 55 from the sprinkling pipes back into the tank 31^a. The collecting trough or reservoir 14^d is formed by a stationary casing 1^a provided with an approximately ring-shaped bottom 13^a from the inner edge of which a vertically 60 disposed flange 12^a projects, and an inwardly and upwardly inclined deflector 16 is arranged over said trough so as to prevent the water which is thrown out from the filter ring from escaping from the machine, the air 65 that escapes from the filter wheel passing

into the collecting chamber 29 between said deflector and the downwardly inclined flange 11^a on the cover 11 which the vanes 9 of the filter wheel support.

While I have herein stated that the various embodiments of my invention herein shown are used for purifying air, I do not wish it to be understood that my broad idea is limited to a machine that is used for this specific purpose as my improved machine 75 may be used for purifying various gases and collecting or extracting some of the constituents of the gases.

Having thus described my invention, what I claim as new and desire to secure by Letters Patent is:

1. A machine of the character described, comprising a rotating filter ring arranged in such a manner that the medium being operated on is drawn inwardly into same and discharged from the exterior thereof, means for introducing a liquid cleansing agent onto the inner surface of said ring, a supply reservoir communicating with said means for supplying the liquid cleansing agent thereto, a tank or other suitable means arranged adjacent said filter member for containing a quantity of the liquid cleansing agent that is used in the machine, and means for automatically conveying or feeding the liquid cleansing agent from said tank into said reservoir.

2. A machine of the character described, comprising a rotating filter ring arranged in such a manner that the medium being operated on is drawn inwardly into same and discharged from the exterior thereof, means for introducing a liquid cleansing agent onto the inner surface of said ring, a supply reservoir communicating with said means for supplying the liquid cleansing agent thereto, a tank or other suitable means arranged adjacent said filter member for containing a quantity of the liquid cleansing agent that is used in the machine, means for automatically conveying or feeding the liquid cleansing agent from said tank into said reservoir, and means for automatically supplying the liquid cleansing agent to said tank.

3. A machine of the character described, comprising a rotating filter ring arranged in such a manner that the medium being operated on is drawn inwardly into same and discharged from the exterior thereof, means for introducing a liquid cleansing agent onto the inner surface of said ring, a supply reservoir communicating with said means for supplying the liquid cleansing agent thereto, a tank or other suitable means arranged adjacent said filter member for containing a quantity of the liquid cleansing agent that is used in the machine, means for automatically conveying or feeding the liquid cleansing agent from said tank into said

reservoir, and means for causing the cleansing agent that escapes from said filter ring to pass into said supply reservoir.

4. In a machine of the character described, a horizontally arranged rotating filter ring that causes the medium being operated on to be drawn into same and discharged from the exterior thereof, a spraying device arranged in said ring for applying a liquid cleansing agent to the inner surface thereof, a collecting reservoir surrounding said filter ring and arranged adjacent the upper end thereof, a connection between said reservoir and spraying device, a tank arranged adjacent the lower end of the filter ring for containing a quantity of the liquid cleansing agent used in the machine, and a rotating means for causing the liquid in said tank to be raised or lifted into said reservoir.

5. In a machine of the character described, a horizontally arranged rotating filter ring that causes the medium being operated on to be drawn into same and discharged from the exterior thereof, a spraying device arranged in said ring for applying a liquid cleansing agent to the inner surface thereof, a collecting reservoir surrounding said filter ring and arranged adjacent the upper end thereof, a connection between said reservoir and spraying device, a tank arranged adjacent the lower end of the filter ring for containing a quantity of the liquid cleansing agent used in the machine, a rotating means for causing the liquid in said tank to be raised or lifted into said reservoir, and blades or vanes on the exterior of said filter ring.

6. In a machine of the character described, a horizontally arranged rotating filter ring that causes the medium being operated on to be drawn into same and discharged from the exterior thereof, a spraying device arranged in said ring for applying a liquid cleansing agent to the inner surface thereof, a collecting reservoir surrounding said filter ring and arranged adjacent the upper end thereof, a connection between said reservoir and spraying device, a tank arranged adjacent the lower end of the filter ring for containing a quantity of the liquid cleansing agent used in the machine, a rotating means for causing the liquid in said tank to be raised or lifted into said reservoir, blades or vanes on the exterior of said filter ring, and means for causing the cleansing liquid that escapes from said ring to enter said reservoir.

7. In a machine of the character described, a horizontally arranged rotating filter ring, a device arranged inside of said ring for applying a liquid thereto, a reservoir surrounding the filter ring and arranged adjacent the upper end thereof, a connection between said reservoir and the

liquid-applying device, a tank arranged adjacent the lower end of the filter ring for containing a quantity of liquid, and means for causing the liquid in said tank to revolve when the filter ring is rotated and pass upwardly into said reservoir. 70

8. In a machine of the character described, a horizontally arranged rotating filter ring, a device arranged inside of said ring for applying a liquid thereto, a reservoir surrounding the filter ring and arranged adjacent the upper end thereof, a connection between said reservoir and the liquid-applying device, a tank arranged adjacent the lower end of the filter ring for containing a quantity of liquid, means for causing the liquid in said tank to revolve when the filter ring is rotated and thus attain sufficient centrifugal force to cause it to pass upwardly into said reservoir, and 85 fan blades or vanes arranged on the exterior of said filter ring.

9. In a machine of the character described, a horizontally arranged rotating filter ring, a device arranged inside of said ring for applying a liquid thereto, a reservoir surrounding the filter ring and arranged adjacent the upper end thereof, a connection between said reservoir and the liquid-applying device, a tank arranged adjacent the lower end of the filter ring for containing a quantity of liquid, means for causing the liquid in said tank to revolve when the filter ring is rotated and thus attain sufficient centrifugal force to cause it 95 to pass upwardly into said reservoir, fan blades or vanes arranged on the exterior of said filter ring, and means for separating the liquid that escapes from the filter ring from the air that escapes from said ring. 100

10. In a machine of the character described, a horizontally arranged rotating filter ring that causes air to be drawn into same and discharged from the exterior thereof, a collecting reservoir arranged outside of said filter ring for containing water that is used for purifying the air which is drawn into the filter ring, means arranged inside of the filter ring and communicating with said reservoir for applying water to the 110 inner surface of said ring, means for maintaining a body of water adjacent the lower end of the filter ring, and means arranged to rotate with said filter ring for causing the water at the lower end of same to be lifted 115 upwardly and discharged into said reservoir. 120

11. In a machine of the character described, a horizontally arranged rotating filter ring that causes air to be drawn into same and discharged from the exterior thereof, a collecting reservoir arranged outside of said filter ring for containing water that is used for purifying the air which is drawn into the filter ring, means arranged 130

inside of the filter ring and communicating with said reservoir for applying water to the inner surface of said ring, means for maintaining a body of water adjacent the 5 lower end of the filter ring, means arranged to rotate with said filter ring for causing the water at the lower end of same to be lifted upwardly and discharged into said reservoir, and a deflector arranged adjacent 10 said reservoir for causing the water that escapes from the filter ring in the form of a spray to enter said reservoir.

12. In a machine of the character described, a horizontally arranged rotating 15 filter ring that causes air to be drawn into same and discharged from the exterior thereof, a device arranged in said filter ring for applying water to the inner surface thereof, a reservoir communicating with said device and arranged in such a manner that the 20 water is supplied to said device under pressure, means for maintaining a body of water adjacent the lower end of the filter ring, and means for causing the water to circulate 25 from said body of water to said reservoir and then through said device while the filter ring is in operation.

13. In a machine of the character described, a rotating filter ring, means for 30 maintaining a body of water adjacent the lower end of said ring, a reservoir arranged in a higher horizontal plane than said body of water, water-applying devices arranged within the filter ring and communicating 35 with said reservoir, and means for causing said body of water to be raised by centrifugal force into said reservoir when the filter ring is in operation so as to maintain a constant circulation of water through the 40 machine.

14. In a machine of the character described, a filter ring, a reservoir arranged outside of the filter ring and adjacent the upper end thereof, a sprinkling device arranged within the filter ring, a feed pipe 45 that connects the lower end of said device with said reservoir, and means for causing a body of water located adjacent the lower end of the filter ring to be raised by centrifugal force into said reservoir.

15. In a machine of the character described, a horizontally arranged filter ring, a reservoir arranged outside of said filter ring and adjacent the upper end thereof, a 55 water-lifting member arranged outside of the filter ring and rotating with same for causing a body of water at the lower end of said filter ring to be raised by centrifugal force into said reservoir, and vanes or blades 60 arranged between said filter ring and said water-lifting member.

16. A machine of the character described, comprising a horizontally arranged filter ring that causes air to be drawn into 65 same and discharged from the exterior

thereof, a device for applying wash water to said filter ring, a reservoir which receives some of the wash water that is discharged from said filter ring, said reservoir being arranged in a higher horizontal plane than 70 said device, and a connection between said reservoir and the device which applies the wash water to the filter ring.

17. A machine of the character described, comprising a horizontally arranged filter 75 ring that causes air to be drawn into same and discharged from the exterior thereof, a device for applying wash water to said filter ring, a reservoir which receives some of the wash water that is discharged from 80 said filter ring, a connection between said reservoir and the device which applies the wash water to the filter ring, said reservoir being so arranged with relation to said device that gravity causes the water to flow 85 to said device, and means for maintaining a sufficient quantity of water in said reservoir to supply said device while the machine is in operation.

18. In a machine of the character described, a rotating filter ring arranged horizontally, means for maintaining a body of water adjacent the lower end of said ring, a reservoir arranged in a higher level than 90 said body of water, devices communicating 95 with said reservoir for applying water to the inner surface of the ring, a valve for automatically controlling the supply to said body of water, and means governed by said body of water for controlling said valve, 100 said valve-controlling means being so constructed that it is not affected or rendered inoperative when said body of water is in a turbulent state.

19. A machine of the character described, comprising a horizontally arranged rotating filter ring, a tank surrounding said filter ring for containing wash water, a collecting reservoir arranged adjacent the upper end of 105 said tank, an approximately inverted cone-shaped rotatable member that causes the water in said tank to be lifted by centrifugal force into said reservoir, blades or vanes arranged between said filter ring and inverted cone-shaped member and extending 110 above said member, a deflector arranged over said reservoir, and a downwardly inclined deflector that rotates with said ring so as to cause the air that passes through 115 said ring to be discharged downwardly and outwardly from the machine.

20. A machine of the character described, comprising a horizontally arranged rotating filter ring, a tank surrounding said filter ring for containing wash water, a collecting 120 reservoir arranged adjacent the upper end of said tank, an approximately inverted cone-shaped member arranged to rotate in said tank so as to cause the water in said tank to be lifted by centrifugal force into 125 130

said reservoir, blades or vanes arranged between said filter ring and inverted cone-shaped member and extending above said member, a deflector arranged over said reservoir, a downwardly inclined deflector that rotates with said ring so as to cause the air that passes through said ring to be discharged downwardly and outwardly from the machine, a valve for controlling the supply of water to said tank, a lever for actu-

ating said valve, and an arm pivotally connected to said lever and provided at its opposite ends with floats.

In testimony whereof I hereunto affix my signature in the presence of two witnesses, 15 this 28th day of May 1910.

JOHN ZELLWEGER.
